UNITED STATES PATENT OFFICE.

CHARLES R. WILLIAMS, OF NEWARK, NEW YORK.

STEP-LADDER.

SPECIFICATION forming part of Letters Patent No. 402,215, dated April 30, 1889.

Application filed December 17, 1888. Serial No. 293,886. (No model.)

To all whom it may concern:

Be it known that I, CHARLES R. WILLIAMS, of Newark, in the county of Wayne and State of New York, have invented a new and useful Improvement in Step-Ladders, which improvement is fully set forth in the following specification, and shown in the accompanying drawings.

The object of my invention is to provide a step-ladder, substantially of common kind, with a folding shelf at one side thereof, so as to be at the right hand of the person standing upon the steps of the ladder, and to operate the shelf automatically by the means and in the manner hereinafter specified. The arrangement of the parts is such that the shelf folds when the parts of the ladder are folded or closed, and is brought to a horizontal position when the ladder is spread for the purpose of use.

The invention is hereinafter more fully described, and particularly pointed out in the claims.

Referring to the drawings, Figure 1 is a side elevation of the upper part of a step-ladder in position for use, the shelf being shown in two positions by full and dotted lines; Fig. 2, a front view of the same; Fig. 3, a horizontal section taken as on the dotted line α in Fig. 1, a part of the step being broken out to uncover parts beneath, various parts being shown in two positions by full and dotted lines; and Figs. 4, 5, and 6, drawn to a larger scale, show forms of one of the connections.

Referring to the parts shown in the drawings, A A are the sides of the step-ladder supporting the steps B B', and C the rear legs or braces of the ladder.

D is a folding shelf attached by hinges a at the right side of the ladder on a level with the step B, next below the upper step of the ladder. The sides A of the ladder are each divided into two parts, b b', with an opening, p, between, and a bar, c, is secured rigidly to the under side of the shelf, the bar being of sufficient length to pass through said opening p and extend some distance under the step B, as shown. This constitutes a strong support for the shelf when in its horizontal position. The shelf is preferably made with a part, e, extending through the opening p to

meet the end of the step B, as shown in Fig. 3.

The shelf is operated automatically by the following means: d is a lever fulcrumed at f 55 to the under side of the step B and provided with a link, g, to connect it with the rear legs or braces, C, of the ladder, as shown. The lever is confined and supported by an angular guard or loop, h, secured to the under surface of the step. i is a rod connecting the lever d with the bar c, the connection being at the edge of the bar at some little distance away from the hinge a. This connecting-rod is joined both to the lever and bar in some 65 simple manner that will admit of a sort of a universal or free movement for it, so that the rod will not bind or cramp when the parts are operated.

It will be understood from the description 70 that when the rear braces or legs, C, are swung away from the sides A A in the act of opening out the ladder, the bar c will be drawn by the connecting-rod in a direction inward, causing the shelf to be brought to a horizontal 75 position, and when the ladder is closed the lower part of the bar will be pushed outward, causing the shelf to be folded up against the side of the ladder, as shown by dotted lines in the various figures, the joints at l and n 80 being made sufficiently free to allow of the swinging motion of the parts.

The joint at o is always at a point below the level of the axis of the hinges a, so that the bar and shelf will always move in obedience 85 to the action of the connecting-rod as the latter is actuated by the lever.

It is desirable to have the connecting-rod joined to the shelf-bar in some manner by which it may be readily detached therefrom, 90 so that the shelf may remain folded and at rest when it is not wished to use it. Figs. 4 and 5 show a form of connection in which the rod is formed with a hook to enter an eye, k, rigid with the bar. In this construction the 95 hook may be raised out of the eye whenever the step-ladder is to be used without the shelf. Fig. 6 shows another simple form in which the end of the connecting-rod is expanded and formed with a key-hole opening, r, to be passed over and back of the head of a screw, s, rigid in the bar. This form also admits of an easy disconnection between the rod and bar.

Guide-pieces *t* are secured to the step *B* to cause the rear legs or braces, *C*, of the step-ladder to come squarely against the sides *A* when the ladder is closed. The outer ends of these guides are inclined or tapered, as shown, to more readily guide the legs to their places. The action of the lever *d* and link *g* sometimes tends to throw the legs *C* toward one side when the ladder is closed. This makes these guides necessary.

What I claim as my invention is—

1. A step-ladder having the side *A* formed with an opening, in combination with a step for the ladder, and a shelf joined to the outer surface of said side *A* and provided with a supporting-bar held in position to pass through said opening in the side *A* and to rest against the under surface of the step, substantially as described.
2. A step-ladder having sides *A*, in combination with a step for the ladder, and a shelf joined by a hinge to a side *A* and having a supporting-bar held to pass through an opening in the side *A* and to bear against the step, said shelf being formed with a part extending through said opening in the side *A* to meet the step, substantially as shown and described.

3. A step-ladder having the side formed with an opening, in combination with a step, rear legs or braces for the ladder, a folding shelf joined to said side by a hinge and provided with a supporting-bar held to pass through said opening in the side, a lever secured to said step, a link connecting said lever and rear braces, and a connecting-rod joining said lever and supporting-bar, substantially as shown and described.

4. A step-ladder having the side formed with an opening, in combination with a step, rear braces for the ladder, a shelf joined to said side by a hinge and provided with a supporting-bar passing through said opening in the side, a lever secured to the step, a link connecting said lever and rear braces, and a rod connecting said lever and supporting-bar, said connecting-rod being detachable from said supporting-bar, substantially as and for the purpose set forth.

CHARLES R. WILLIAMS.
